UNITED STATES PATENT OFFICE.

THOMAS BENJAMIN LEECH, OF LEYTONSTONE, AND THOMAS LANE, OF BLACKWALL, ENGLAND; SAID LANE ASSIGNOR TO SAID LEECH.

ANVIL FOR MAKING TANKS, CISTERNS, BOXES, OR THE LIKE.

SPECIFICATION forming part of Letters Patent No. 787,927, dated April 25, 1905.

Application filed January 18, 1904. Serial No. 189,591.

To all whom it may concern:

Be it known that we, THOMAS BENJAMIN LEECH, manager, residing at 10 Lemna road, Leytonstone, in the county of Essex, and 5 THOMAS LANE, engineer, residing at 28 Orchard Place, Blackwall, in the county of Middlesex, England, subjects of the King of Great Britain, have invented a certain new and useful Improved Anvil for Making Tanks, Cis- 10 terns, Boxes, or the Like, of which the following is a specification, reference being had to the drawings hereunto annexed and to the letters marked thereon.

The invention relates to improvements in 15 means employed in the manufacture of metal tanks, cisterns, boxes, or the like.

According to a former invention of one of us—namely, the said Thomas Benjamin Leech—the ordinary method of constructing 20 metal tanks, cisterns, or the like by riveting the plates together at the angles was dispensed with and in lieu thereof said plates were joined at the angles by means of long clips of pec- 25 cular construction which embraced the re- turned or flanged edges of the plates. The side joints thus formed were closed by means of a bar-like anvil and a tilt-hammer, but the joints at the top and bottom of the tank were closed by hand, rivets being afterward inserted 30 at the corners and the tank dipped in the galvanizing-bath.

Now the primary object of the present invention is to provide means whereby the closing of the joints of the top and bottom of the 35 tank may also be accomplished by the aid of a tilt-hammer or the like, thus effecting a considerable economy in time and labor and improving the finish of the tank.

In the accompanying drawings, Figure 1 is 40 a side elevation, partly in section, of an anvil constructed according to the present invention with a tank in position thereon and a co-acting tilt-hammer. Fig. 2 is a vertical section of parts taken on the line 1 1 of Fig. 1.

Fig. 3 is a side elevation of the top of the anvil. Fig. 4 is a plan thereof. Fig. 5 is a front elevation of the top of the anvil. Fig. 6 is a sectional view of parts, showing a joint at an angle of a tank resting upon the anvil

prior to the closing of the seam. Fig. 7 is a similar view, but showing the parts after the closing of the joint with the hammer in action. Fig. 8 is a similar view to Fig. 1, but illustrating a modified method of mounting the anvil. Fig. 9 is a front elevation thereof, partly in section; and Fig. 10 is a sectional elevation of a modified form of pillar, showing a tank in position.

In the several figures like parts are indicated by similar letters of reference, and Figs. 3 to 7 are drawn to an increased scale with respect to the other figures of the drawings.

Referring to Figs. 1 to 7, *a* represents the floor upon which the workman stands. *b* represents a pillar or standard which supports 60 the anvil. *b'* represents the anvil. *c* represents the hammer. *c'* represents the head of the hammer, which is shaped to coact with the anvil. *d* represents a tank in position upon the anvil for the closing of one of the bottom 70 joints by the hammer, and *d'* represents a joint at one of the angles.

The pillar *b* is sunk below the floor *a* in order to bring the anvil *b'* to a convenient height for the workman, and at its upper end it is 75 formed with a crank or offset *b'*, the object of which is hereinafter explained, and which at its outer extremity is provided with a vertical hole or bearing *b''*.

In the hole or bearing *b''* is revolvably mounted 80 the reduced end of a short spindle or stud *b''*, which takes a bearing upon the crank or offset *b'* and is fastened in position by a nut *b''*, screwing upon the threaded lower end of the spindle *b''* and a washer *b''*, which takes a bearing 85 against the under side of the crank or offset *b'*.

Upon the upper end of the spindle *b''* is fixed 90 the anvil *b'*, which is formed with a tapered hole or socket therein which receives the correspondingly-tapered upper end of the spindle *b''*, upon which the anvil is driven and securely held by friction.

The anvil consists of a bar, square in cross-section, and it is mounted upon the spindle *b''* 95 in such manner that a line drawn vertically therethrough would intersect two of its angles, the upper one of said angles constitut-

ing the surface upon which the work is performed, while the anvil is of a length considerably less than that of a joint, and it is unequally mounted upon the spindle b^3 in order 5 to facilitate the insertion thereof into the tank d by the manhole d^2 thereof and for the purpose hereinafter described.

By reason of its short length and unequal mounting the anvil b^6 is incapable of supporting a joint for its entire length, as will be seen on reference to Fig. 2, and it is therefore necessary to turn the anvil through an arc of one hundred and eighty degrees, as shown by the dotted lines in Fig. 4, and in order to 15 complete the joint and to insure its being turned into correct position in either direction a horizontal stud or projection b' is fixed upon the spindle b^3 and coacting stops b^8 are provided upon the cranked upper end b' of the 20 post or standard b .

It will be understood upon reference to Fig. 1 that the object of forming the pillar b with the crank or offset b' is to bring the anvil b^6 into the required central position with relation to the tank notwithstanding that the manhole d^2 , through which the pillar b is introduced, necessarily occupies an eccentric position when the tank d is resting upon the anvil in the required manner.

30 The mechanism for actuating the tilt-hammer c is of a very ordinary character; but a short reference to the principal parts thereof may assist persons unskilled in the use of such machines to better understand the same. The 35 arm of the hammer is pivotally mounted at c^2 , beyond which point it is acted upon by tappets c^3 , carried by a wheel c^4 , by which it is intermittently raised and released, while the sudden descent of the hammer is assisted 40 by a spring c^5 . The wheel c^4 is constantly driven through suitable intermediate gearing from a pulley c^6 , driven by a belt c^7 , and in order that said belt may be tightened so as to set the machine in motion at the will of the 45 workman a lever c^8 , pivotally mounted at c^9 , is at its upper end provided with a jockey-roller c^{10} , adapted to impinge upon the belt c^7 and at its lower end is provided with a cam or incline c^{11} , adapted to be acted upon by a 50 stud or roller c^{12} , carried by a pedal-lever c^{14} to bring the jockey-roller c^{10} into action, a spring c^{12} being employed to impart the return movement to the lever c^8 .

The method of constructing a tank, aided 55 by the means hereinbefore described, is as follows: The four sides d of the tank are first loosely jointed together by clips d' . The top d^3 is then similarly connected to the sides d , after which the joints d' , connecting the side plates 60 d , are closed by means of a tilt-hammer and an ordinary anvil consisting of a long fixed horizontal bar. The tank thus partly made is then removed to the anvil b^6 , constructed according to the present invention, which is inserted

through the open bottom of the tank, and the 65 four joints d' at the angles connecting the top d^3 with the sides d are closed by the tilt-hammer c . One half of each joint is first closed with the anvil b^6 in one position. The tank is then 70 raised and said anvil is turned and the tank 75 adjusted to the required position upon the anvil, and the other half of each joint d' is similarly closed. The tank d is now removed from the anvil b^6 , and the bottom d^4 thereof is loosely jointed to the sides d by clips d' , as 80 hereinbefore described with respect to the other joints, and the tank is passed over the anvil by way of the manhole d^2 , when the four joints d' , connecting the bottom d^4 with the sides d , are closed in a similar manner to that 85 described with respect to the top d^3 . The whole of the joints having been closed in the manner above described the tank is removed from the anvil, a conical rivet is inserted at each of the eight corners, and the tank is subsequently immersed in the galvanizing-bath 95 in the usual way.

In the example given at Figs. 8 and 9 the anvil b^6 instead of being pivotally mounted upon the crank or offset b' of the pillar b is 100 constructed to slide endwise with relation to the stud b^3 in order to shift the same from one part of a joint d' to the other. For this purpose the upper end of the stud b^3 is formed with a V-shaped saddle b^9 , adapted to embrace 105 the lower angle of the anvil b^6 and provided longitudinally thereof with hook-like flanges or projections b^{10} , which engage corresponding undercut grooves or ways b^{11} , formed in the anvil b^6 , while the anvil is provided with 110 projections b^{12} , by the aid of which it may be shifted upon the saddle b^9 , and which also act as stops to limit its extreme movement in 115 either direction.

In the example given at Fig. 10 a modified 105 form of pillar is shown, in which the pillar b instead of being formed with a cranked offset b' is itself bent or curved in order to bring its upper end into the required central position, and the stud or spindle b^3 is formed with 110 an annular groove b^{13} , which is engaged by a set-screw b^{14} in order to hold the stud against vertical movement while permitting it to rotate.

It will be obvious that the anvil b^6 may be 115 usefully employed for closing joints of other descriptions than the clip-joints hereinbefore described or for riveting in similar situations. It will also be understood that the details of construction of the device may be 120 otherwise considerably modified without departing from the spirit of the invention.

By the means hereinbefore described the top and bottom joints of a tank or the like may be closed with the same efficiency as the 125 side joints, while at the same time said operation is facilitated and cheapened.

Having now particularly described and as-

certained the nature of the said invention and in what manner the same is to be performed, we declare that what we claim is—

1. In means employed in the manufacture of metal tanks, cisterns, boxes, or the like, a vertical pillar adapted to pass through a hole in the tank and having a horizontal crank at its upper end, a vertical stud at the end of said crank and an anvil having an inverted-**V**-shaped upper edge supported by said stud substantially as herein shown and described and for the purpose stated.

2. In means employed in the manufacture of metal tanks, cisterns, boxes, or the like, a vertical pillar adapted to pass through a hole in the tank and having a horizontal crank at its upper end, a vertical stud revolvably mounted at the end of said crank and an anvil having an inverted-**V**-shaped upper edge sup-

ported by said stud substantially as herein shown and described and for the purpose stated.

3. In means employed in the manufacture of metal tanks, cisterns, boxes, or the like, a vertical pillar adapted to pass through a hole in the tank and cranked to bring its upper end into the required central position with relation to the tank and an adjustable anvil having an inverted-**V**-shaped upper edge supported by the upper end of said pillar substantially as herein shown and described and for the purpose stated.

THOMAS BENJAMIN LEECH.
THOMAS LANE.
